UNITED STATES PATENT OFFICE.

GARRETT F. EMCH, OF WOODVILLE, OHIO.

AUTOMATIC FIRE-ALARM APPARATUS.

1,029,179.

Specification of Letters Patent. Patented June 11, 1912.

Application filed August 30, 1911. Serial No. 646,926.

To all whom it may concern:

Be it known that I, GARRETT F. EMCH, a citizen of the United States, and a resident of Woodville, in the county of San-dusky and State of Ohio, have invented a certain new and useful Automatic Fire-Alarm Apparatus; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to electrical fire signal apparatus, and has for its object the provision of an improved apparatus of this character which is simple and efficient in its construction and operation, inexpensive of manufacture, and capable of being easily and quickly installed, thus enhancing the practicability and commercial value thereof.

The invention is fully described in the following specification, and while in its broader aspect, it is capable of embodiment in numerous forms, a preferred embodiment thereof is illustrated in the accompanying drawings, in which,

Fig. 1 is a front elevation of a touch-off comprising my invention in set position. Fig. 2 is an end view thereof with a signal bell and battery in circuit therewith, and Fig. 3 is a perspective view of a building with a portion broken away, and with my invention shown in association therewith.

Referring to the drawings, "A" designates a touch-off unit of my invention, which is shown in the present instance, as comprising a base block 1 and the fixed and movable electrical contact parts 2 and 3, respectively, which are insulatingly carried by said base in any suitable manner.

The movable contact part 3 is shown in the present instance as comprising a strip of spring metal, which is bent upon itself to form two leaves or fingers 4 and 5, the former of which is fixed to the block 1, as by the securing of a laterally bent flange 6 thereto, while the other one of such leaves is normally movable by its spring action into contact with the fixed contact part 2, which is disposed in suitable position for such purpose. The movable leaf or finger 5 is held in retracted or set position relative to the

contact part 2 by a band or ring 7, which encircles the free end portions of the leaves 4 and 5 to prevent a relative outward springing thereof, and is composed of wire or other suitable material, a part at least of which is of an easily fusible nature.

The contact parts 2 and 3 are in series through a wire 8 with an electric bell or other signal device 9 and a source of electrical supply as a battery 10, the wire terminals being connected to the parts 2 and 3 by binding posts 11 or in any other suitable manner.

In the use of my improved signaling device a plurality of the units "A" are located at different points within a building as indicated in Fig. 3, with the movable contact part 5 of each unit held in spaced relation to its companion contact part 2 by a fusible member 7, as indicated in the drawings, or in any other suitable manner. The units are held connected in circuit with a source of electrical supply 10 and an electrical signaling device 9, the latter of which is located within an adjoining building or at any suitable point where it may be desired to give an alarm. When a fire occurs in a building adjacent to any of the touch-off units "A" the heat of the fire very quickly burns off the wire or fuse 7 thus permitting the contact part 5 to spring into contact with the part 2 and close the signal circuit to effect an energizing of the signal device 9 to give the alarm.

It is apparent that I have provided a simple and efficient device for giving an alarm of fire as soon as one starts within a building equipped with the touch-off units, and that such units are inexpensive of construction, and can be easily and quickly installed.

I wish it understood that my invention is not limited to any specific construction or arrangement of the parts except in so far as such limitations are specified in the claim.

Having thus described my invention, what I claim as new and desire to secure by Letters Patent, is,—

In a device of the character described, a touch-off unit having a fixed contact part and a movable contact part disposed in a common electrical signal circuit, the movable part comprising a member which is fixed relative to the fixed part and having the edge thereof adjacent to the fixed part bent laterally and extended at both ends

22
with one extension bent over the remaining portion of such bent edge and lying adjacent thereto and influenced to normally move outwardly therefrom into contact with the 5 fixed part and a fusible member coacting with said extensions to retain the movable extension out of contact with said fixed part.

In testimony whereof, I have hereunto signed my name to this specification in the presence of two subscribing witnesses.

GARRETT F. EMCH.
